UNITED STATES PATENT OFFICE

160,599

COMBINED HOUSEHOLD HEATER AND LAUNDRY DRIER

George B. Herbster, Cleveland, Ohio, assignor to Herbster-Schmiler, Inc., Cleveland, Ohio, a corporation of Ohio

Application March 1, 1949, Serial No. 1,159

Term of patent 14 years

(Cl. D81—2)

To all whom it may concern:

Be it known that I, George B. Herbster, a citizen of the United States and a resident of Cleveland, county of Cuyahoga, and State of Ohio, have invented a new, original, and ornamental Design for Combined Household Heater and Laundry Drier, of which the following is a specification, reference being had to the accompanying drawing, forming a part thereof.

In said annexed drawing:

Fig. 1 is a perspective view of a combined household heater and laundry drier, as viewed from the front and one side, embodying my new design; and Fig. 2 is a perspective view thereof as viewed from the rear and side shown in Fig. 1. The side not shown is plain.

I claim:

The ornamental design for a combined household heater and laundry drier, as shown and described.

GEORGE B. HERBSTER.
